UNITED STATES PATENT OFFICE

2,633,873

ELASTIC SURFACE LINER FOR ABRASIVE SERVICE

Daniel E. Stines, Plainfield, N. J., assignor to Standard Oil Development Company, a corporation of Delaware

Application October 11, 1947, Serial No. 779,231

1 Claim. (Cl. 138—62)

1

The present invention relates to a means for preventing erosion of the interior surfaces of flow lines and vessels in a system for handling fluidized solids, and to an elastic surface liner for such service.

In the handling of finely divided solid materials, for example powdered catalyst materials suspended in a stream of liquid or gas, the abrasive action of the finely divided fluidized material moving through a conduit system at comparatively high velocity causes extensive erosion of the surfaces with which the particles come in contact. The abrasive action is particularly noticeable at points of direct impingement of the particles, as a result of sudden changes in direction of flow. Various means have been employed to alleviate the effect of such abrasive action. Surface hardening of the inner walls of flow lines, special alloy, hardened inserts, and surface coating of materials having a surface resiliency or elasticity, such as rubber, plastics and the like, have been used. Under certain conditions some of these expedients have been satisfactory, but none of them have combined resistance to high temperature and chemical action with the characteristic of surface elasticity which has been found most effective in resisting the erosive effect of impingement of finely divided solid particles traveling at high velocity.

It is an object of the present invention to provide a lining material for flow lines and vessels containing abrasive solid particles in motion. More particularly it is an object of the invention to provide a fabricated lining composed of materials which while not necessarily having the inherent characteristic of surface elasticity are so fabricated and used as to produce a lining material which has that characteristic, and also the ability to withstand high temperatures, above 800° F., and chemical action of substances brought into contact with it.

These and other objects of the invention may be fully understood from the following specification when read in conjunction with the accompanying drawing, in which

Figure 1 is a plan view of a portion of a liner material according to this invention, enlarged to show the detail thereof;

Figure 2 is a sectional view of a portion of a liner material as shown in Fig. 1, taken along the line II—II thereof;

Figure 3 is a longitudinal section through a portion of a conduit member, showing a liner material according to Figs. 1 and 2 as applied to the inner surface of such a member.

As illustrated in Figs. 1 and 2, the lining material is fabricated with a base woven of a fine drawn wire, the warp 1 and woof 2 being of a metal or alloy having such characteristics of hardness, resistance to temperature, chemical action, and to abrasion, as may be desired. This base is provided with a resilient pile surface or nap formed of a plurality of tufts 3. Each tuft is composed of a cluster of individual fibres of a material similar to that of the base, and the several tufts are individually secured to the warp or woof elements of the base, by spot welding, indicated at 3a in Fig. 2, or otherwise, in alternating closely spaced rows. In securing the tufts to the base they are disposed so that they extend angularly outwardly from the base and are inclined in one general direction, with the unsecured ends of the tufts in one row substantially overlapping the secured ends of the tufts in an adjoining row so as to produce a thatched effect, whereby the tufts extend substantially concurrent with and in the direction of flow of solid material over the liner material.

The liner material as described with reference to Figs. 1 and 2 may be formed or shaped to fit the interior of any conduit member such as a pipe or vessel, and secured to the inner surface area thereof as by means of spot welding or clips, or in any other conventional and suitable manner. As illustrated in Fig. 3, a pipe 4 is provided with a liner 5 of the material as illustrated in Figs. 1 and 2, which liner is disposed within and secured to the inner surface of the pipe 4 so that the individual tufts 3 all extend in the general direction of flow through the pipe as indicated by directional arrows in the drawings.

When thus constructed, the liner provides a surface in which the individual elements have a yielding, resilient, and springy resistance to the impact of the individual particles of a finely divided solid material which may strike against them. Thus, although these individual elements are of a material which in itself does not possess the characteristic of surface elasticity, when fabricated as described, a lining material is formed which acquires the characteristic of surface elasticity while retaining the inherent ability of the basic material to resist the effect of temperature or chemical action. Naturally, the individual elements forming the nap or pile of the liner material will be subject to abrasion, although to a lesser extent than a plain surface, and therefore the lining is removable and replaceable as required in service.

In the form of the invention illustrated and described, it is contemplated that the diameter

of the individual fibres forming the nap or pile of the liner will be in the neighborhood of about 0.005 inch, while that of the fibres in the woven base will be about 0.04 inch, spaced from one another in the fabric at about 0.12 inch.

I claim:

In an apparatus for handling finely divided solid materials, including a conduit member which defines a confined flow path for such materials as a fluidized stream thereof, an abrasion resistant liner for the inner surface of a conduit member, comprising a substantially rigid, deformable woven base of metallic fibres, including warp and woof elements thereof, said base rigidly secured to and conforming with the inner surface area of a conduit member, and a plurality of individual tufts of finely drawn metallic fibres, said tufts individually secured to said base woof elements by one end and in substantially parallel rows, said tufts extending outwardly from said base in substantially uniform angular relation thereto, and in the direction of flow through such conduit member, the unsecured ends of said tufts in one row substantially overlapping the secured ends of the tufts in an adjacent row in the direction of flow through such conduit member, whereby said tufts collectively provide a substantially resilient impact surface in which individual tuft fibres are free to flex under impact of individual, moving par-

ticles of said stream of solid material, without substantial separation of said particles from said stream.
